DESIGN FOR A MOTION PICTURE PROJECTOR

Herman A. De Vry, Chicago, Ill.

Application August 24, 1936, Serial No. 64,541

Term of patent 7 years

To all whom it may concern:

Be it known that I, Herman A. De Vry, a citizen of the United States, residing at Chicago, in the county of Cook and State of Illinois, have invented a new, original, and ornamental Design for a Motion Picture Projector, of which the following is a specification, reference being had to the accompanying drawing, forming part thereof.

Fig. 1 is a view in side elevation of the projector;

Fig. 2 is a view in side elevation at right angles to Fig. 1;

Fig. 3 is a plan view.

The opposite side of the projector, as shown in Fig. 1, is substantially the same as the side illustrated, the part shown in broken lines in Fig. 1 having been omitted from Figs. 2 and 3 for convenience of illustration.

I claim:

The ornamental design for a motion picture projector as shown and described.

HERMAN A. DE VRY.
